UNITED STATES PATENT OFFICE.

PAUL GEORGE FRAUENFELDER, OF METUCHEN, NEW JERSEY, ASSIGNOR,
BY MESNE ASSIGNMENTS, TO THE AMERICAN LITHOGRAPHIC COMPANY,
OF NEW YORK.

ART OF MULTICOLOR PRINTING.

SPECIFICATION forming part of Letters Patent No. 565,891, dated August 18, 1896.

Application filed May 29, 1893. Serial No. 475,994. (No specimens.)

To all whom it may concern:

Be it known that I, PAUL GEORGE FRAUENFELDER, a citizen of the Republic of Switzerland, residing at Metuchen, in the county of 5 Middlesex and State of New Jersey, have invented a new and useful Improvement in the Art of Multicolor Printing, of which the following is a specification, reference being had to the accompanying drawings, forming part 10 hereof.

The invention relates to the art of multicolor printing.

It has for its object to reduce the expense and time involved in such printing and in 15 the preparations therefor, and to improve the result.

It consists in the improved methods and product herein described and claimed.

Heretofore in the art of multicolor printing 20 as practiced industrially the procedure has in general been as follows: A separate and distinct printing-surface has been prepared for each separate color employed, and has been prepared with the full drawing and the 25 full values required for that particular color in the finished print, and the printing from each such printing-surface has been by a direct impression upon the final paper to receive the print, the several colors being thus 30 applied in succession and by as many successive impressions as there are colors to be printed. That is to say, there are as many printing-surfaces as there are colors, and the paper that is receiving the print is passed 35 through the printing-press as many times as there are colors to be printed, and naturally and inevitably each color becomes substantially dry before the next color is or can be applied. It is a necessary incident of this 40 method of procedure that each printing-surface (of which there are as many as there are colors to be printed) must be prepared by the artist with the same elaborate care and detail as if it were to be the only printing-surface; 45 that is to say, it must be prepared with the full drawing and full values desired for that particular color in the finished print. It is the elaborate preparation by artists of this plurality of printing-surfaces that constitutes

a large proportion of the whole time and cost 50 of multicolor printing as practiced heretofore, especially in the more artistic and advanced productions of the art, and especially where several, as, say, eight or ten or a dozen, colors are employed. Again, it is a necessary 55 incident of the method of procedure heretofore employed that the mixing or blending or combining of colors in the finished print (at one and the same point or on one and the same line) for the sake of the modified color 60 effect so obtained is limited to such mixing or blending or combining as can be accomplished by the printing of one color upon the top of another color that has been previously printed, and it is rather an optical blending 65 than an actual physical blending of the separately-printed colors, being rather due to the juxtaposition of those separately-printed colors in fine dots or lines, or to the partial transparency of the overlying layer or layers, 70 this partial transparency permitting underlying layers of a different color to have some effect on the eye of the observer. It is also an incident of the method of procedure heretofore employed that a careful examination 75 of the finished print in detail will disclose the presence thereon of as many different and distinct drawings as there had been different colors separately printed. An examination of any product of the prior art under 80 a strong magnifying-glass will illustrate and enforce the statements made above. Modifications of this old method of multicolor printing have been suggested and sometimes used, such as inking different parts of the 85 length of a color-roller with different-colored inks, thus producing stripe effects in the print, employing separable printing-surfaces that are mechanically separated for inking with different-colored inks and are brought 90 together again for printing, and inking portions of the printing-surface with one color-roller and complementary portions with another color-roller, the two color-rollers being cut out so as to be complements the one 95 of the other; and it has been suggested to blend two contiguous colors along their edges by making those colors on the color-rollers

overlap slightly for that purpose; but these are not substantial departures from the method first above described.

I have discovered that it is possible to combine, that is to say, to physically mix and blend, a plurality of colors, as, say, eight or ten colors, more or less, on one printing-surface, and then to print from said printing-surface by one impression a finished and complete multicolor print, finished and complete so far as the combination of colors printed are concerned, and that this can be done by employing graduated pattern-surfaces, one for each color, the graduations of each pattern-surface predetermining the amount of color to be taken up by it, and one printing-surface graduated for the final print, that is to say, for the aggregate of colors to be printed at one impression, this printing-surface by reason of its graduations taking up from the pattern-surfaces, either directly or through suitable intermediate surfaces, a predetermined amount of color; and I have discovered that this can be successfully done without the careful and elaborate graduations in full drawing and full values of more than one surface, that is, the final printing-surface itself, and also that the blending of colors is more perfect in method and in result, and gives wider range for artistic effects than is possible in the methods of procedure heretofore employed. Again, I am enabled by my process to produce accurate and harmonious blends of wide range at a greatly-reduced expenditure of time and skill, and to produce prints that are perfect in their drawing and values, (because they contain and show the impression of the drawing and values of only one surface, to wit, the final printing-surface,) and that contain and show only one uniform layer or film of coloring-matter over the face of the drawing, but a layer or film of coloring-matter that changes as desired from dot to dot and line to line into new colors and shades of color, and that is shaded off and blended gradually, as desired, one color into another and in any direction on the face of the print.

In carrying out my invention in its preferred form I proceed as follows: I prepare by hand or by any of the ordinary processes (such as by transferring a half-tone negative) on a printing-surface (such as lithograph stone, zinc, wood, steel, copper, celluloid, gelatin, &c.) the full drawing and full color values desired in the print that is to be produced. Reverse offset impressions of the drawing upon this printing-surface are then made on surfaces which, whether used flat or curved around cyclinders or rollers, come later on to form the pattern-surfaces. These pattern-surfaces, or any of them, can be made out of any of the substances above named or of substances suitable for a printing or a pattern surface. I prefer, however, to employ zinc both for the pattern-surfaces and for the printing-surface. As many pattern-sur-

faces are prepared with reverse offset impressions as in the judgment of the artist may seem best. Thus if the artist thinks 70 twelve colors necessary to produce the print, twelve reverse offset impressions are made upon as many different pattern surfaces or plates. On each of these pattern surfaces or plates drawings (that need be only rough 75 drawings) are made by hand, by photography, or by any of the graphic methods, wherever that color or any of the compound colors of which it is to be an element is desired in the print, the reverse offset impressions being used as a guide only in the placing of the drawings and being then obliterated. The offsets are really needed only when the drawing on the pattern-surfaces is done by hand. These pattern-surfaces are then 80 prepared and made ready for printing by any of the ordinary methods, as by etching, as if they were to be printed from. If desired, the portions that are to bear ink may be raised in relief, but I prefer to make them plano-graphic, that is, so that they are neither raised in relief nor sunk in intaglio, but are set approximately on the same plane as those portions of the pattern-surface that are not to bear ink. The ink-bearing portion of one 95 or more, but preferably of all, of the pattern-surfaces is so prepared as to be capable of taking up the ink from the ink-rollers onto its surface in graduated quantities, whereby the printing-surface (prepared in full values) 100 is enabled, when brought into contact with the pattern-surfaces, to take up the inks therefrom in quantities graduated to correspond to the final colors and blends of colors and values of colors desired. Their respective colors are then applied to the pattern-surfaces by color-rollers or in any suitable way, and they are pressed ink-side down against the final printing-surface in proper succession, the said printing-surface having 105 been first cleaned and prepared for the inking, care being taken to have each pattern-surface register with the printing-surface when pressed upon the latter. The printing-surface now carries all the colors located, 110 blended, and graduated as they are desired to appear in the print. The printing is now done from the printing-surface by one impression on paper or whatever other substance it is desired should receive the final print. 115

In carrying out my new process the ultimate printing-surface, called herein the "printing-surface," is the only one of the plurality of surfaces prepared that requires to be prepared with the full drawing and full values 120 in graduation desired in the print, and it requires to be prepared with the full drawing and full values in graduation of the aggregate of all the colors the combined effect of which it is desired to produce in the print. 125 The separate pattern-surfaces prepared need be prepared only with approximate graduations, that is to say, with approximately the drawing and values required for the color con- 130

cerned. It is sufficient if this preparation of the separate pattern-surfaces is only approximate, and, as it were, in the rough, and this is by reason of the fact that on the final printing-surface the full and accurate drawing and the full and accurate values in graduation for the aggregate of all the colors exist. When the colors are applied to the pattern-surfaces that are thus roughly and rapidly prepared, as indicated, there is by reason of this preparation of the pattern-surfaces a preliminary selection and graduation of the coloring-matter taken up from the color-rollers, and when in turn that pattern-surface is pressed against the face of the printing-surface, accurately registering with the same, there is a second and now accurate selection and graduation of the coloring-matter taken up from the pattern-surface. The ink-bearing portions of two or more of the pattern-surfaces are preferably so constructed and arranged as to make an overlap to form a blend in one or more portions of their impressions on the printing-surface.

In order to prevent the first color deposited upon the printing-surface from being picked off by the pattern-surfaces applied for the second and subsequent colors, the said pattern-surfaces are in the well-known way kept damp in those parts which do not carry any ink, or if this damping is not desired the pattern-surfaces can be etched or cut in relief in any ordinary well-known way, as in making the ordinary printing-plate, so that the raised parts only will touch the printing-surface, those being at the same time the parts that carry the ink. The printing-surface will also in the well-known way be dampened after each printing operation and before receiving a series of fresh impressions from the pattern-surfaces, where the printing-surface is a planographic surface, and the pattern-surfaces will be dampened in the usual way after each transference of color to the printing-surface, where they are planographic surfaces. It will also be understood that the pattern-surfaces (two or more or all of them) may be applied to and yield up their coloring-matter in proper succession to a paper or other suitable intermediary or transferring surface, and the aggregate of all the colors so obtained upon such surface be afterward transferred at one impression to the printing-surface and thereafter printed at one impression from said printing-surface. It will also be understood that my new process may be used and the new print that is the result of it may be made, and prior thereto or subsequently thereto other printing may be done on the same paper or print-receiving surface. This prior or subsequent printing on the same print-receiving surface would not, of course, negative the fact of the use of my new process or the production of my new product in so far as the colors applied by it and in it are concerned. I prefer in practice, for instance, to apply a portion of all the colors desired in

the finished print according to my new process and thereby to produce, as to such colors, my new product, and subsequently to apply 70 by one or more impressions the balance of the colors, also again according to my new process, and so producing again as to such balance of colors my new product, printing the second and subsequent prints directly 75 over and upon the first print and registering accurately therewith.

The accompanying drawings illustrate the printing-surface and pattern-surfaces for a complete print. The print selected has eight 80 colors.

Figure 1 represents the printing-surface before the application thereto of the pattern-surfaces. The remaining figures represent the several pattern-surfaces to be applied to the printing-surface and are numbered in the order of their successive application to the printing-surface to prepare the printing-surface for the impression. Fig. 2 represents the pattern-surface for the purple; Fig. 3, 90 the pattern-surface for the vermilion; Fig. 4, for brown; Fig. 5, for neutral gray; Fig. 6, for buff; Fig. 7, for light green; Fig. 8, for pink; Fig. 9, for yellow.

In examining the various drawings it must 95 be borne in mind that in all the pattern-surfaces, Figs. 2 to 9, inclusive, the drawings are laterally reversed in relation to that on the impression or printing surface, Fig. 1. It will be noted that but little drawing is required on the pattern-surfaces. For instance, in the pattern-surface for the light green, Fig. 7, the background is but roughly and approximately drawn or graduated, instead of being carefully drawn, as heretofore required, and 100 its selection of color from its plain color-roller is but approximately graduated, but when 105 this pattern-surface is applied to the printing-surface, Fig. 1, that printing-surface takes up from it and selects the color in the accurate proportion and graduation required for 110 the final impression. The other pattern-surfaces that contribute to this background, buff, 115 Fig. 6, and yellow, Fig. 9, also contain but little drawing, and yet the aggregate of these 120 colors upon the printing-surface produces an accurate and handsome print. So, also, it will be noted that the main color, purple, Fig. 2, of the parasol is obtained with but rough drawing and roughly-approximated values on 125 the pattern-surface, but nevertheless this color is accurately selected and taken up by the printing-surface in the desired proportion for the final impression. So, also, of the face, the 130 dress, and all other parts of the print. The double selective action makes possible the most delicate shading and the most desirable blending of the colors and permits the blending before printing and the printing all at one impression and according to one single unitary drawing.

The new and improved product produced by my new process is clearly distinguishable from what is old. It combines the perfection

of drawing of a print that is printed in one color at one impression from one printing-surface with the variety of coloring and of shading and graduation of coloring of a print 5 that is printed in many colors by many successive impressions from as many different printing-surface; and as an accompaniment of the combination there is in addition in my improved print a perfection of mixing 10 and blending and shading and intershading of tints and colors, according to the graduations of the pattern-surfaces and of the printing-surface and obtained by their double and successive selective action and as described, 15 that has not been attainable heretofore.

I am aware that different colors have been printed at and by one impression of a single printing-surface and that various expedients have been suggested for inking the printing-surface with the different colors, and hence I 20 do not broadly claim the printing of different colors at one impression, nor do I broadly claim the inking of a single printing-surface with different colored inks. I am aware also 25 that it has even been suggested to blend two colors for such a printing-surface, and I do not broadly claim the mixing or blending of colors for such a printing-surface.

I believe myself to be the first to successfully 30 produce a multicolor print requiring and showing a graduation of color or shading effects at and by one impression of a single printing-surface, and the first to attain such graduations of color by the double and successive 35 selective action of separate graduated pattern-surfaces taking up color separately from a color roller or rollers and a graduated printing-surface taking up color successively from said pattern-surfaces.

40 What I claim, and desire to secure by Letters Patent, is—

1. The improvement in the art of multicolor printing which consists in constructing a series of properly-prepared graduated pattern-surfaces, each of which, by means of its 45 graduations, selects a predetermined amount of color, constructing a printing-surface with graduations suitable for the final print which, by means of its graduations, selects a predetermined amount of each color, inking the pattern-surfaces each with its proper color, inking the printing-surface successively from the pattern-surfaces, and finally printing from the printing-surface, substantially as 50 shown and described.

2. As an improvement in the art of multicolor printing the process which consists in constructing a series of properly-prepared planographic pattern-surfaces, each of which, by means of its preparation, selects a predetermined amount of color, constructing a printing-surface with graduations suitable for the final print which, by means of its 60 graduations, selects a predetermined amount of each color, inking the pattern-surfaces each with its proper color, inking the printing-surface successively from the pattern-surfaces, and finally printing from the printing-surface, substantially as 65 shown and described.

faces, and finally printing from the printing-surface, substantially as shown and described.

3. As an improvement in the art of multicolor printing the process which consists in constructing a series of properly-prepared zinc pattern-surfaces, each of which, by means of its preparation, selects a predetermined amount of color, constructing a printing-surface with graduations suitable for the final print, which, by means of its graduations, selects a predetermined amount of each color, inking the pattern-surfaces each with its 70 proper color, inking the printing-surface successively from the pattern-surfaces, and finally printing from the printing-surface substantially as shown and described.

4. As an improvement in the art of multicolor printing the process which consists in constructing a series of properly-prepared zinc pattern-surfaces, each of which, by means of its preparation, selects a predetermined amount of color, constructing a zinc printing-surface with graduations suitable for the final print which, by means of its graduations, selects a predetermined amount of each color, inking the pattern-surfaces each with its 75 proper color, inking the printing-surface successively from the pattern-surfaces, and finally printing from the printing-surface substantially as shown and described.

5. As an improvement in the art of multicolor printing the process which consists in constructing a series of graduated pattern-surfaces, each graduated approximately according to the drawing and the values required for its color in the final print, and each of which, by means of its graduations, 80 selects a predetermined amount of color, constructing a printing-surface with graduations in full drawing and full values suitable in the final print for the aggregate of colors to be printed, inking the pattern-surfaces each 85 with its proper color, inking the printing-surface successively from the pattern-surfaces, and finally printing from the printing-surface, substantially as shown and described.

6. The improvement in the art of multicolor printing which consists in constructing a series of properly-prepared graduated pattern-surfaces, each of which, by means of its 90 graduations, selects a predetermined amount of color, two at least of which are so constructed and arranged as to make an overlap 95 to form a blend in one or more portions of their impressions on the printing-surface, constructing a printing-surface with graduations suitable for the final print which, by 100 means of its graduations, selects a predetermined amount of each color, inking the pattern-surfaces each with its proper color, inking the printing-surface successively from the pattern-surfaces, and finally printing from the printing-surface, substantially as 105 shown and described.

7. An improved multicolor print made substantially as described at one impression from

5 a printing-surface constructed with graduations suitable for the final print, and inked successively from a series of separate color pattern-surfaces each having properly-prepared graduations, the separate colors being first selected by the graduations of the pattern-surfaces and subsequently selected therefrom by the graduations of the printing-surface and mixing and blending together on 10 said printing-surface in the quantities and with the arrangement predetermined by this double selective action, the resulting mixed and blended colors being printed and existing in the finished multicolor print substantially as one layer of coloring-matter arranged 15 according to the unitary drawing of one printing-surface.

8. An improved multicolor print made substantially as described at two or more impressions, each impression being made from a 20 printing-surface constructed with graduations

tions suitable for the final print, and inked successively from a series of separate color pattern-surfaces each having properly-prepared graduations, the separate colors being 25 first selected by the graduations of the pattern-surfaces and subsequently selected therefrom by the graduations of the printing-surface and mixing and blending together on said printing-surface in the quantities and 30 with the arrangement predetermined by this double selective action, the resulting mixed and blended colors being printed and existing in the finished multicolor print substantially as one layer of coloring-matter arranged 35 according to the unitary drawing of one printing-surface.
